(57) **CLAIM**

The ornamental design for a drip pan, as shown and described.

DESCRIPTION

FIG. 1 is a top perspective view of a drip pan showing my new design;

FIG. 2 is a front view thereof, rear, left and right views being omitted since they are identical to the front view;

FIG. 3 is a top view thereof;

FIG. 4 is another top perspective view thereof;

FIG. 5 is a bottom perspective view thereof; and,

FIG. 6 is another bottom perspective view thereof.

The surface shading on the surfaces indicates the tinfoil material.
